UNITED STATES PATENT OFFICE.

HARRY WILLIAM THORNTON, OF WINONA, MINNESOTA, ASSIGNOR TO
EDWARD L. WALLWORK AND GEORGE R. THORNTON, OF CHICAGO,
ILLINOIS.

DANCING TOY.

No. 845,985.

Specification of Letters Patent.

Patented March 5, 1907.

Application filed August 6, 1906. Serial No. 329,450.

To all whom it may concern:

Be it known that I, HARRY WILLIAM THORNTON, a citizen of the United States, residing at Winona, in the county of Winona and State of Minnesota, have invented a new and useful Dancing Toy, of which the following is a specification.

The invention relates to improvements in dancing toys.

10 The object of the present invention is to improve the construction of dancing toys and to provide a simple and efficient one having leg-joints corresponding in operation to those of the human figure and adapted to closely resemble the movements of a person in clog-dancing.

With these and other objects in view the invention consists in the construction and novel combination of parts hereinafter fully described, illustrated in the accompanying drawing, and pointed out in the claims here-to appended, it being understood that various changes in the form, proportion, size, and minor details of construction within the scope of the claims may be resorted to without departing from the spirit or sacrificing any of the advantages of the invention.

In the drawing, Figure 1 is a perspective view of a dancing toy constructed in accordance with this invention and shown in position for use. Fig. 2 is a side elevation of the same, one of the feet being in section. Fig. 3 is a front elevation of the same, one of the feet being also in section.

35 Like numerals of reference designate corresponding parts in all the figures of the drawing.

1 designates a dancing figure provided with a body portion 2, having a socket 3 at its rear edge for the reception of a rod or handle 4, which has one end tapered and detachably fitted in the said socket. The figure, which may be constructed of any suitable material, is provided with legs composed of upper and lower sections or members 5 and 6. The upper sections or members 5 of the legs are secured to the body 2 at opposite sides of the lower end thereof by means of a transverse pivot 7, which permits 45 the legs to swing bodily backwardly and forwardly from a vertical position. The lower end of the upper section 5 is reduced to form a tongue 8, which is fitted in a slot or bifurcation 9 of the upper end of the lower section

or member 6 of the legs, and the reduced portion or tongue 8 is secured in the said slot or bifurcation by means of a transverse pivot or pin 10. The reduced lower end of the upper section or member forms opposite shoulders 11, which are inclined downwardly and forwardly, as clearly shown in Fig. 2 of the drawing, and which are arranged to be engaged by the upper edges 12 of the lower section or member 6, whereby the swinging or pivotal movement of the upper and lower sections on each other is limited. The upper edge of the lower section or member 6 engages the front portion of the inclined shoulders 11 when the leg sections or members are in substantial alinement, and the rear corners of the upper end of the lower section or member 6 are rounded at 13, which permits the leg to bend rearwardly in a manner similar to the human leg. When the lower section or member 6 is in engagement with the inclined lower shoulder of the upper member or section 5, the two members or sections are arranged at a very slight angle to each other, as shown in Fig. 2 of the drawing, so that an upward pressure or blow on the lower end of the legs will always tend to bow or bend the same at the knee-joints.

The lower ends 14 of the legs are pivoted by pins or rivets 15 in slots 16 of feet 17, consisting of oblong blocks. The lower sections 85 or members 6 of the legs are pivoted adjacent to the rear end walls of the slots 16, so as to limit the downward swing of the feet from a horizontal position in a manner similar to the ankle-joint of the human figure. The front edges of the lower sections of the legs are spaced sufficiently from the front walls of the slots 16 to permit a comparatively free upward swing of the feet. The lower faces of the feet are shaped to form rear heel portions 90 and are convexly curved in advance of the same.

The upper portion of the body of the figure is shaped into a head, and arms 18 are pivoted to the body at the shoulder portions 100 thereof. The figure may be ornamented and shaped to present the desired appearance and to represent various characters, and it is operated by means of a vibratory platform 19, consisting of a thin board having a circular outer portion 20. The inner end of the board is placed upon a chair or other seat upon which the operator sits, as clearly

- illustrated in Fig. 1 of the drawing, and the handle or stick of the figure is held in the left hand, with its legs loosely resting upon the vibratory platform, which is struck with the right hand, the blow causing the platform to vibrate and strike the feet of the figure. As the movements permitted by the joints of the legs of the dancing figure are limited as in the human figure, the toy when operated will closely resemble the movements of a person in a clog-dance, and by holding the figure in slightly different positions with relation to the vibratory platform the step may be changed.
- 15 The toy is easily operated and does not require an experienced operator to secure amusing results, as the joints of the legs permit the latter to swing only backwardly and forwardly and prevent any lateral oscillation of the legs or the members thereof.

Having thus fully described my invention, what I claim as new, and desire to secure by Letters Patent, is—

1. In a dancing toy, the combination with a vibratory platform, of a figure consisting of a body portion, upper leg members pivoted to the body portion to swing backwardly and forwardly, lower leg members pivoted to the upper leg members, the pivots connecting the said members being arranged transversely of the figure, and the said members being provided with abutting faces engaging each other when the leg members are in substan-

tial alinement and limiting the forward swing of the lower members, and feet provided with 35 openings to receive the lower member and pivoted to the same, the rear walls of the openings being arranged to engage the lower members for limiting the downward swing of the feet, and a handle-rod connected with 40 the figure.

2. In a dancing toy, the combination with a vibratory platform, of a figure consisting of a body portion, upper leg members pivoted to the body portion to swing backwardly and 45 forwardly, lower leg members pivoted to the upper leg members, the pivots connecting such members being arranged transversely, and the said members being provided with means for limiting the forward swing or 50 movement of the members on each other at the knee-joint when the said members are in substantial alinement, and feet pivoted to the lower members and provided with means for engaging the same to limit the downward swing of the feet and to permit an upward swing of the same in excess of the downward swing, and a handle connected with the figure. 55

In testimony that I claim the foregoing as my own I have hereto affixed my signature in the presence of two witnesses.

HARRY WILLIAM THORNTON.
